DESIGN FOR A MEASURING SPOON

Carl E. Bretney, Toledo, Ohio

Application March 26, 1947, Serial No. 137,900

Term of patent 3½ years

(Cl. D44—29)

To all whom it may concern:

Be it known that I, Carl E. Bretney, a citizen of the United States, and a resident of Toledo, Lucas County, Ohio, have invented a new, original, and ornamental Design for a Measuring Spoon, of which the following is a specification, reference being had to the accompanying drawing, forming a part thereof.

In the drawing:

Figure 1 is a top perspective view of a measuring spoon, showing my new design; and

Figure 2 is a side elevation of the measuring spoon.

I claim:

The ornamental design for a measuring spoon, as shown.

CARL E. BRETNAY.
